CLAIM

The ornamental design for a splice coupler, as shown and described.

DESCRIPTION

FIG. 1 is a front top perspective view of a splice coupler in accordance with an embodiment of the invention;

FIG. 2 is rear bottom perspective view of the splice coupler of FIG. 1;

FIG. 3 is a top plan view of the splice coupler of FIG. 1;

FIG. 4 is a bottom plan view of the splice coupler of FIG. 1;

FIG. 5 is a front elevation view of the splice coupler of FIG. 1;

FIG. 6 is a rear elevation view of the splice coupler of FIG. 1;

FIG. 7 is a right side elevation view of the splice coupler of FIG. 1; and,

FIG. 8 is a left side elevation view of the splice coupler of FIG. 1.

The broken dash lines shown in the figures are for the purpose of defining the bounds of the claimed design. The broken dash lines themselves form no part of the claimed design.

1 Claim, 2 Drawing Sheets
